UNITED STATES PATENT OFFICE.

GUSTAV C. PAHLOW, OF GALESBURG, ILLINOIS, ASSIGNOR OF ONE-HALF TO HENRY J. OLSON, OF GALESBURG, ILLINOIS.

COFFIN-HANDLE.

1,302,423.

Specification of Letters Patent. Patented Apr. 29, 1919.

Application filed February 20, 1919. Serial No. 278,189.

To all whom it may concern:

Be it known that I, GUSTAV C. PAHLOW, a citizen of the United States, residing at Galesburg, in the county of Knox and State 5 of Illinois, have invented a new and useful Coffin-Handle, of which the following is a specification.

The device forming the subject matter of this application is a handle, adapted to be 10 used on coffins and other receptacles, and the invention aims to provide novel means whereby, when the grip portion of the handle is raised, a part of the grip will be distorted or bent, so as to form a permanent 15 pivotal connection between the grip and the base member of the handle.

It is within the province of the disclosure to improve generally and to enhance the utility of devices of that type to which the invention appertains.

With the above and other objects in view, which will appear as the description proceeds, the invention resides in the combination and arrangement of parts and in the 25 details of construction hereinafter described and claimed, it being understood that, within the scope of what is claimed, changes in the precise embodiment of the invention shown can be made without departing from the 30 spirit of the invention.

In the accompanying drawings:

Figure 1 shows in front elevation, a device constructed in accordance with the invention; Fig. 2 is a horizontal section, showing the parts as they will appear after the grip has been permanently connected with the base member; Fig. 3 is a sectional view similar to Fig. 2, but showing the parts, as they will appear when the bending of a portion of the grip is about to take place; and Fig. 4 is a view similar to Fig. 2 but showing the parts as they will appear after a portion of the grip has been bent to form a permanent pivotal connection between the grip and the base member.

The numeral 1 marks a base member, preferably made out of metal and having an opening 2 across which a pivot bar 3 extends. The numeral 4 marks a grip, which may be 50 variously constructed, without jeopardizing the utility of the invention. As shown, but not necessarily, the grip is trough-shaped in cross section, and is provided at its lower end with a tongue 5 having a reverse bend 6. 55 Ears 7 project inwardly from the side por-

tions of the grip, and engage the bend 6 of the tongue 5, to hold the tongue about a side bar 8.

In the side walls of the grip 4, at the upper end thereof, slots 9 are formed, the slots 60 defining bendable tongues 10 having depending lugs 11. On its top, and near to its upper end, the grip 4 may be supplied with a transverse rib 12.

Let it be supposed that the parts are in the 65 condition shown in Fig. 3. Then, the upper end of the grip 4 may be inserted readily into the opening 2 of the base member 1, the pivot bar 3 being received in the slots 9. The lugs 11 engage the base member 1 at the 70 lower edge of the opening 2, and when the grip, which is made of metal, is raised into the position shown in Fig. 4, the grip fulcrums on the pivot bar 3 and the tongues 10 engage the base member at the lower edge of 75 the opening 2, the tongues 10 being bent upwardly at their free ends, thereby to diminish the width of the slots 9, at the inner ends thereof, as shown at 14. The grip 4 is now assembled securely but pivotally with the 80 bar 3, and, although the grip may be swung upwardly and downwardly as occasion may demand, the grip cannot be retracted out of the opening 2 and be removed from the pivot 85 bar 3. When the grip 4 is raised and in use, as indicated in Fig. 4, rib 12 bears against the base member 1 above the opening 2, and coöperating with the pivot bar 3, receives a portion of the weight.

In practical operation, the inner end of the 90 grip 4 simply is inserted into the opening 2 and the outer end of the grip is raised, whereupon the grip will be securely but pivotally assembled with the bar 3, in the manner hereinbefore set forth.

Having thus described the invention, what is claimed is:

1. A handle comprising a base member having an opening and provided with a pivot bar extended across the opening and 100 a grip insertible into the opening and having a slot receiving the pivot bar, the slot defining a bendable finger in the grip, the finger coöperating with the base member at the lower edge of the opening, when the 105 grip is raised, to secure a bending of the finger, a partial closing of the slot, and a permanent pivotal mounting of the grip on the pivot bar.
2. A handle comprising a base member 110

having an opening and provided with a pivot bar extended across the opening; and a grip insertible into the opening and having a slot receiving the pivot bar, the slot defining a 5 bendable finger in the grip, the finger having a lug adapted to engage the base member at the lower edge of the opening, the finger and the lug coöperating with the base member, when the grip is raised, to secure a bending 10 of the finger, a partial closing of the slot,

and a permanent pivotal mounting of the grip on the bar.

In testimony that I claim the foregoing as my own, I have hereto affixed my signature in the presence of two witnesses.

GUSTAV C. PAHLOW.
